A. HAYWARD.
FIRE PLACE.

Patented Sept. 25, 1834.

Decr 25 1834

437

Asstl. S. Hayward, of Easton, Massachusetts,

Letters Patent,

The schedule referred to in the following Patent and making part of the same, containing a description in the words of the said Asstl. Hayward himself of his improvement in the common Cast Iron fire place.

Know to all to whom these presents shall come, Asstl. Hayward of Easton in the County of Bristol & Commonwealth of Massachusetts, Cabinet-Maker and Greciter, aforesaid, declaring that he has invented a new and useful improvement in the construction of the common fire place, and that the following is a full and exact description of the construction and use of said improvement, as invented by him. — This improvement consists in applying to the common cast iron, or other metal fire frame, a cast or wrought iron hot air chamber, of any form or of any size which may be found most convenient (that in the accompanying model is made cylindrical) which air chamber is fixed near the top of the fire frame, and so that the ascending smoke and flame, shall pass over and around it in part, it being so placed as to make part of the smoke flue, and the top of the fire frame, is cut in a funnel shape to accommodate said air chamber, the pillars in front are cast hollow, through one or both of which a current of cold air obtained from such source as may be desired, is made to pass and communicate with said air chamber, by a metal pipe as is shown in the model, or in any other way which may be practicable, a thin metal plate, making a fixed or moveable bottom, is made to lay in said air chamber and reaching its entire length a little elevated from the permanent bottom, and so constructed at

Drawing

the cold air enters, so that it may pass first past the
bottom of the air chamber, between the permanent &
feeding pipes, and then reach the opposite end of
the air chamber, so as to have a hole cut for the purpose in
said false bottom, through which it passes, and re-passing
the whole length of the air chamber is then discharged
into the room, in a heated state, through an orifice above
the feeding pipe, connected with the air chamber, to which
the feeding pipe is attached, and on the valve is a valve
constructed and formed, so to shut off the cold air, by
closing the mouth of the feeding pipe, and also to close
at the same time the discharging orifice when required, &
this valve is especially useful and necessary when the
air chamber is used as an oven for which it is particularly
designed, when used to pass hot air into the room.
On the end of the air chamber, opposite that at which
the cold air is supplied, is attached a common oven
door, and by shutting the valve as before mentioned
an oven of the most convenient form is at once made.
The accompanying model fully illustrates my said improve-
ment in all its parts, but the form may be varied at
pleasure, --- able that I claim as my said inven-
tion notwithstanding what may be herein before stated
is the application of a hot air chamber near the top of
the common fire frame, supplied with cold air through one
or both of the front pillars or otherwise for the double purpose
of heating rooms and affording an oven always ready for
use, I also claim as my invention the circular form of
the top of the fire frame whether used for a hot air chamber
or not --- In testimony that the above is a true spe-
cification of my said improvement as above described, I

have witnessed and my hand this thirty first day of July in
the year of our Lord, one thousand eight hundred and thirty
four
